Primary Examiner — Sharon S Oum(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing in the environment of a ceiling fan, showing my new design;

FIG. 2 is a bottom perspective view of the ceiling fan motor housing of FIG. 1;

FIG. 3 is a top view of the ceiling fan motor housing of FIG. 1;

FIG. 4 is a bottom view of the ceiling fan motor housing of FIG. 1;

FIG. 5 is a front side view of the ceiling fan motor housing of FIG. 1;

FIG. 6 is a rear side view of the ceiling fan motor housing of FIG. 1;

FIG. 7 is a right side view of the ceiling fan motor housing of FIG. 1; and,

FIG. 8 is a left side view of the ceiling fan motor housing of FIG. 1.

The broken lines illustrate portions of the ceiling fan motor housing and ceiling fan environment that form no part of the claimed design.

1 Claim, 8 Drawing Sheets(56)
